ATTORNEYS

UNITED STATES PATENT OFFICE.

CHRIST T. CHRISTIANSON, OF BROOKLYN, MARYLAND.

AUTOMOBILE-HOOD.

1,381,166.

Specification of Letters Patent. Patented June 14, 1921.

Application filed July 9, 1920. Serial No. 395,067.

To all whom it may concern:

Be it known that I, CHRIST T. CHRISTIANSON, (a Norwegian, who have declared my intention to become a citizen of the United States,) at present residing at Brooklyn, in the county of Anne Arundel and State of Maryland, have invented certain new and useful Improvements in Automobile-Hoods, of which the following is a specification.

10 My invention has for its object to provide an automobile hood or cover with a simple and inexpensive means that is readily adjustable from the driver's seat for admitting air around the engine and other parts of the operating mechanism, for cooling purposes, and my said invention comprises a peculiar arrangement of shutter device coöperative with an air slot or passage in the hood side and in which is included a simple and effective means for holding the said shutter device rigid and against rattling, when shifted to any of the adjustments, partially or wholly opened to the air.

15

20

With other objects in view that will be hereinafter further explained, my invention consists in the peculiar construction and novel arrangement of the parts outlined in the following detailed description, specifically pointed out in the appended claim and 30 illustrated in the accompanying drawings, in which:

Figure 1 is a perspective view of so much of the hood end of an automobile as is necessary to illustrate a practical application of 35 my invention.

Fig. 2 is a horizontal section of a hinged hood member and a portion of the vehicle dash, with my improvements applied, the shutter device and the control therefor being 40 shown at the closed position in full lines and at an open position in dotted lines.

Fig. 3 is an inside face view of a hinged hood member with the shutter and the shutter control devices thereon.

45 Fig. 4 is a detail longitudinal section, taken substantially on the line 4—4 on Fig. 2, of the shifting or pull device on the dash and its connection with the shutter control member hereinafter specifically referred to.

50 Referring to the accompanying drawing in which like numerals indicate like parts in all of the figures, 1 designates a portion of a hood of a conventional type of motor vehicle and 2 designates one of the hinged sides 55 thereof.

In the practical application of my invention, my improvements are applied to a side hood section of the conventional shape and size with the usual hinge loops 20 along the upper edge, whereby, when desired, my hood side with the improvements thereon may be readily substituted for an old hinge hood side by simply withdrawing the usual hinge pintle or rod to permit of removing the old side and retaining the said pintle, when my improved hinge member 2 is substituted therefor, it being understood that my new hood member in practice is equipped with lock lugs 21—21 for coöperating with the usual hold down devices 22—22, as indicated 70 on Fig. 1.

In the development of my invention, the hood member 2 is formed with an elongated horizontal opening 23 that extends a length, more or less, that of the distant space that 75 takes in the usual series of air slots in the regular form of hood side.

In my arrangement, fixed shutter plates 24—24 are riveted to the inside of the hood member to extend a short distance over the 80 opening 23 therein at each end thereof, as is clearly shown in Fig. 3, the said plates 24—24 constituting the solid abutments for the end ones 30—30 of a series of shutter blades 3, in practice of sheet metal, and 85 adapted for folding flatwise upon themselves to constitute a complete closure for the opening 23, when shifted to the position shown in full lines on Fig. 2.

4—4 designate angle plates that extend 90 along the upper and lower edges of the opening 23 and rivet thereto, as is best shown in Fig. 3, by reference to which it will also be seen each shutter blade 3 has a pintle 31 at the upper and lower ends for engaging hinge 95 apertures 40—40 in the angle plates 4—4.

To provide for readily working all of the shutter blades in unison, each of the said blades has an inwardly extended horizontal crank-like member 5 and the said members 100 5—5 are pivotally joined to lateral apertured lugs 60 on a control lever 6, one end of which is yieldingly connected, by a tension spring 7, to a fixed lug on the inside of the forward end of the hinge hood member 2. 105

The other or innermost end of the lever 6 has a crank member 61 that loosely fits over the upturned or crank end 80 of a pull lever 8 which rides on a bearing plate 90 that is integral with a sleeve-like head 9 shaped for 110

being readily and fixedly held in an aperture made in the dash and provided, along its lower edge, with a series of ratchet or lock teeth 82 for coöperating with the lower 5 ratchet edge 92 of the pull lever 8, as is best shown in Fig. 4.

From the foregoing description taken in connection with the drawings, the complete construction, the manner of its use and the 10 advantages of my invention will be readily understood by those familiar with the use of devices of this kind.

It will be observed from the drawings that by connecting the control lever 6 through 15 a crank portion 60 with a crank member 80 on the pull handle 8, as shown, a simple and yet effective means for connecting the control lever with the actuating handle is provided that allows for quickly fitting the parts and 20 holding them to their coöperative position without the use of clamps, nuts or other kindred means and it also provides for the necessary shifting of the connection between the control lever 6 and the pull member 8 25 during the operation of opening and closing the shutter blades.

The tension spring 7 provides for holding the control lever 6, the shutter blades and the connection between the members 6 and

8 in a substantially rigid relation and against 30 rattling, when the automobile is in motion.

What I claim is:

In an air control for automobile hoods, a hood member having an elongated air passage, a series of shutter blades pivotally 35 mounted on the inside of the hood cross-wise of the opening therein and to fold flat-wise upon one another, a control lever to which all of the blades are individually pivoted, the said control lever including an 40 inwardly projected angle member; in combination with means for adjusting the shutter blades to their partially or wholly closed positions, the said means comprising a horizontal bearing plate having a sleeve-like 45 head portion adapted for being fitted through the vehicle dash and having ratchet teeth, and a pull lever slidably mounted on the bearing plate to work through the sleeve-like head thereof, the said lever including a 50 crank-like member with which the angle member on the control lever slidably interlocks, the said pull lever having a ratcheted edge for interlockably engaging the ratchet teeth on the bearing member whereby to lock 55 the control lever to the adjusted positions.

CHRIST T. CHRISTIANSON.
